United States Patent

Des. 240,282
Patented June 15, 1976

240,282

HEEL OF A SHOE

Jack Horowitz, 48—53 208th St., Bayside, N.Y. 11364,
and Arthur Goldman, 67—66 108th St., Forest Hills,
N.Y. 11375

Filed July 19, 1974, Ser. No. 489,911

Term of patent 14 years

Int. Cl. D2—04

U.S. Cl. D2—325

FIG. 1

FIG. 2

FIG. 1 is a side elevational view of a heel of a shoe showing our new design, the opposite side being identical thereto.

FIG. 2 is a rear elevational view thereof.

The top surfaces, not shown, are plain and follow the top-side contours.

We claim:

The ornamental design for a heel of a shoe, as shown.
